(57) **CLAIM**

The ornamental design for a multifunctional geometric ruler, as shown and described.

DESCRIPTION

FIG. 1 is a front elevational view of a multifunctional geometric ruler showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines illustrate portions of the multifunctional geometric ruler and also represent boundaries of unclaimed portions of the multifunctional geometric ruler that form no part of the claimed design.
